UNITED STATES PATENT OFFICE.

AMEEN AYOB, OF SPOKANE, WASHINGTON.

ATTACHMENT FOR SEWING-MACHINES.

1,122,243.

Specification of Letters Patent. Patented Dec. 29, 1914.

Application filed October 2, 1913. Serial No. 793,002.

To all whom it may concern:

Be it known that I, AMEEN AYOB, a citizen of the United States, residing at Spokane, in the county of Spokane, State of Washington, have invented certain new and useful Improvements in Attachments for Sewing-Machines, of which the following is a specification.

My invention relates to attachments for 10 sewing machines and it provides a fan device which is simple in construction, cheap to manufacture, and easily attached and detached to or from any sewing machine. It provides a means of circulating the air 15 in the room, in which the sewing machine to which the device is attached stands, and it eliminates the expense of providing an electric fan or other means of circulating the air. Furthermore it only requires an 20 inappreciable amount of power to operate. It is particularly advantageous in tailor 25 shops and dressmakers' establishments where one or more sewing machines are operating in a room where a number of people are working, for it serves to keep the atmosphere in motion, and the machines may be distributed that the fan on one machine will cool the operator of another machine.

Referring to the drawings attached here- 30 to and forming a part of this specification: Figure 1 shows a fan constructed according to my invention and applied to a sewing machine. Fig. 2 is a front elevation of a fan constructed according to my invention. 35 Fig. 3 is a side elevation view of the fan shown in Fig. 2. Fig. 4 is a rear elevation view of the fan. Fig. 5 is a view similar to that shown in Fig. 2 but showing the fan in a position to show the lugs of the clamping 40 member. Fig. 6 is a section on line X-X of Fig. 2. Fig. 7 is a modified form of my fan.

An embodiment of my invention shown in the drawings consists of a fan having a 45 number of blades 1, 2, 3 and 4 disposed radially from a central portion 5. To the central portion 5 of a fan I attach a clamp member 6. This clamp member 6 consists of a circular sleeve portion formed in three 50 parts. The part 7 carries integral therewith the bent arms 8 and 9 connected by the member 11 integral therewith. The fan is carried by the connecting portion 11 and is secured thereto by any suitable means such 55 as the stud 10 extending through the fan

and secured by the nut. This stud 10 is integral with the portion 11 connecting the arms 8 and 9, and it also carries the projecting pins 12 and 13 thereon which extend through holes drilled in the central 60 portion of the fan. These pins serve to keep the fan from turning on the stud 10 and with respect to the clamp member. The member 7 of the clamp carries the two parts 14 and 15 hinged thereto at 16 and 17, 65 respectively. These hinged parts serve to complete the sleeve portion of the clamping member and also carry the upstanding lugs 18 and 19 through which the bolt 20 passes. This clamping member is adapted to go onto 70 the drive shaft 21 of the sewing machine 22, and when the clamp is tightened up by means of the nut 23 on the bolt 20 the fan will revolve when the sewing machine is 75 operated.

It will be seen different sizes of fans may be substituted on the clamp by simply removing the nut from the stud 10 and putting on another fan adapted to fit on the pins and stud.

I may find it preferable in adapting my invention to light household sewing machines to construct the fan as shown in Fig. 7, of a metal frame work 24 and cover the blades with fabric 25, instead of using a 85 metal fan.

It is understood that I do not limit myself to any particular type of sewing machine or shape of fan, but may make such modifications as fall within the scope of my claims. 90

What I claim is:

1. An attachment for sewing machines comprising in combination, a clamping member consisting of a split sleeve portion, a bow integral therewith and extending outwardly therefrom, lugs integral with said bow, hinge members mounted on the edges of the split in said split sleeve and adapted to be clamped together, a fan having apertures therein adapted to receive said lugs, 100 said fan being adapted to be mounted on said bow, and means for securing said fan in place.

2. An attachment for sewing machines comprising in combination, a clamping member consisting of a split sleeve portion, a bow integral therewith and extending outwardly therefrom, lugs integral with said bow and adjacent the central portion thereof, a stud mounted on said bow and con- 110

centric with the axis of said split sleeve, clamping means for said split sleeve, and a fan having therein apertures adapted to fit over said lugs, said fan being adapted 5 to be retained on said bow portion by means of said stud.

In testimony whereof I affix my signature in presence of two witnesses.

AMEEN AYOB.

Witnesses:
